(57) **CLAIM**

The ornamental design of the helmet-shaped bottle, as shown and described.

DESCRIPTION

FIG. 1 is a perspective view of the helmet-shaped bottle; FIG. 2 is a side view of the helmet-shaped bottle of FIG. 1, the other side view being a mirror image thereof; FIG. 3 is a front view of the helmet-shaped bottle of FIG. 1; FIG. 4 is a rear view of the helmet-shaped bottle of FIG. 1; FIG. 5 is a top view of the helmet-shaped bottle of FIG. 1; FIG. 6 is a bottom view of the helmet-shaped bottle of FIG. 1; FIG. 7 is a perspective view of an alternative embodiment of the helmet-shaped bottle;

FIG. 8 is a side view of the helmet-shaped bottle of FIG. 7, the other side view being a mirror image thereof;

FIG. 9 is a front view of the helmet-shaped bottle of FIG. 7; FIG. 10 is a rear view of the helmet-shaped bottle of FIG. 7; FIG. 11 is a top view of the helmet-shaped bottle of FIG. 7; and,

FIG. 12 is a bottom view of the helmet-shaped bottle of FIG. 7.

The broken line portions of the drawings are for illustrative purposes only and form no part of the claimed design.
